(57) **CLAIM**

The ornamental design for a catheter package, as shown and described.

DESCRIPTION

FIG. 1 is a front perspective view of a catheter package, showing the new design;

FIG. 2 is a rear elevational view thereof. The front elevational view being a mirror image thereof;

FIG. 3 is a right side elevational view thereof;

FIG. 4 is left side elevational view thereof;

FIG. 5 is a top plan view thereof;

FIG. 6 is a bottom plan view thereof;

FIG. 7 is a front perspective view of a second embodiment of a catheter package, showing the new design;

FIG. 8 is a rear elevational view thereof. The front elevational view being a mirror image thereof;

FIG. 9 is a right side elevational view thereof;

FIG. 10 is left side elevational view thereof;

FIG. 11 is a top plan view thereof;

FIG. 12 is a bottom plan view thereof;

FIG. 13 is a front perspective view of a third embodiment of a catheter package, showing the new design;

FIG. 14 is a rear elevational view thereof. The front elevational view being a mirror image thereof;

FIG. 15 is a right side elevational view thereof;

FIG. 16 is left side elevational view thereof;

FIG. 17 is a top plan view thereof; and,

FIG. 18 is a bottom plan view thereof.

The broken line extending from the top edge of the catheter package shown in FIGS. 1-2 and FIGS. 13-14 represents perforations and form part of the claimed design.

The broken line extending from the top edge of the catheter package shown in FIGS. 1-2 and FIGS. 13-14 represents perforations and form part of the claimed design.

The broken line showing perforations in FIGS. 7-8 and the generally rectangular section of the catheter package in FIGS. 13 and 14 bounded by broken lines on the top, bottom and one side of said section and by dash-dot-dash line on the other side of said section are included for the purpose of illustrating environmental structure and form no part of the claimed design.

1 Claim, 3 Drawing Sheets
